UNITED STATES PATENT OFFICE

2,504,646

COLLAPSIBLE BATHTUB

Mary Brunettie Burrow, Corpus Christi, Tex.

Application March 5, 1946, Serial No. 652,181

5 Claims. (Cl. 4—177)

1

The invention as described herein, and illustrated in the accompanying drawings, consists of a bath tub, an object of which is to provide a tub so formed that it may be collapsed to the substantial thickness of a piece of bed clothing whereby it may be placed beneath a bedridden person as is a bed sheet without having to lift the person and the side walls of the tub then raised to hold water or medicated or medicinal liquid.

Another object of the invention is to provide a collapsible tub, the side walls of which may be raised after a patient has been placed therein.

A further object of this invention is to provide a tub of rubber or waterproofed material having inflatable side walls whereby they may be caused to raise vertically.

A still further object of the invention is to provide in a flexible tub means whereby the side walls thereof may be adjustably held in vertical position.

Other features and advantages will become more readily apparent from the following description and the accompanying illustrative drawings in which:

Figure 1 is a top plan view of the invention.

Figure 2 is a sectional view taken on line 2—2 of Figure 1.

Figure 3 is a side elevational view of Figure 1, the tub being shown collapsed.

Figure 4 is a sectional view taken on line 4—4 of Figure 1.

While one embodiment of the invention is illustrated in the above referred to drawings, it is to be understood that it is merely for the purpose of illustration and that various changes in construction may be resorted to in the course of manufacture in order that the invention may be utilized to the best advantage according to circumstances which may arise, without in any way departing from the spirit and intention of the device which is to be limited only in accordance with the appended claims. And while there is stated the primary field of utility of the invention it remains obvious that it may be employed in any other capacity wherein it may be found applicable.

In the accompanying drawings, and in the following specification, the same reference characters are used to designate the same parts and elements throughout and in which 10 has reference to the complete invention which consists of a collapsible, preferably rubber, tub 11, all of the walls, 12, 13, 14, 15, and 16, are doubled and so spaced as to provide relatively narrow intercom-

2

municating cavities 17, 18, 19, 20, 21, 22, 23, and 24 in the side end and bottom walls between the respective spaced inner and outer sections 25 and 26 and whereby all of the said cavities may be inflated through a tube 27, in order to erect and hold erect all of the side walls and the inner layer 28 of the bottom wall. The device may be employed on a suitable support, as the mattress 29. Cavity 24 is centrally enlarged in order to form a pillow 29 when the device is inflated. The said layer 28 of the bottom wall may be caught transversely to the bottom outer layer 30 of the bottom wall 16, as indicated at lines 31, 32, and 33, in order to provide tuftings 34 upon which an invalid may more comfortably lie. Projecting through one of the side walls (15 for instance) is a tube 35 having a cut off valve 36 and through means of which tube water in the tub may be drawn off.

The above described tub may easily be slipped under a bedridden person and then inflated and water or other liquid poured in to bathe or soak the patient and the device may be as easily removed by withdrawing the liquid and deflating the tub.

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention, that which is claimed to be new and desired to be procured by Letters Patent is:

1. A collapsible tub comprising inflatable walls, an inflatable bottom connecting and communicating with said walls, said bottom having a lower layer and a spaced upper layer, valve means extending through one of said walls, said upper layer spaced and sloping relative to said bottom layer for assisting in draining.

2. A collapsible tub comprising inflatable walls, an inflatable bottom connecting and communicating with said walls, said bottom having a lower layer and a spaced upper layer, valve means extending through one of said walls, said upper layer spaced and sloping relative to said bottom layer for assisting in draining, a raised portion in said upper layer and spaced from said walls for receiving a person's head thereon.

3. A collapsible receptacle comprising resilient walls, means for inflating said walls, a resilient lower member attached to said walls, an upper resilient member fixed to said lower member and spaced therefrom forming an air pocket therebetween, said upper resilient member slopingly disposed with respect to said walls, valve means associated with a wall and positioned at substantially the lowest slope portion of said upper member.

4. A collapsible receptacle comprising resilient walls, means for inflating said walls, a resilient lower member attached to said walls, an upper resilient member fixed to said lower member and spaced therefrom forming an air pocket therebetween, said upper resilient member slopingly disposed relative to one of said walls, valve means associated with a wall and positioned at substantially the lowest slope portion of said upper member, said inflating means comprising a tube communicating with one of said walls.

5. A collapsible bath tub receptacle compris-

ing resilient walls, means for inflating said walls, a resilient lower member attached to said walls, an upper resilient member slopingly fixed to said lower member and spaced therefrom forming an air pocket therebetween, said upper resilient member sloping downwardly toward one of said walls, valve means associated with a wall and positioned at substantially the lowest slope portion of said upper member, said inflating means comprising a tube communicating with one of said walls, an enlargement in said upper member spaced from said walls for resting a portion of a person's body thereon.
